(57) **CLAIM**

The ornamental design for a wireless integrated antenna, as shown and described.

DESCRIPTION

A portion of the disclosure of this patent document contains material, which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a perspective view of a wireless integrated antenna showing our new design;

FIG. 2 is a front view thereof;

FIG. 3 is an enlarged partial view of portion "A" in FIG. 2;

FIG. 4 is a rear view thereof;

FIG. 5 is a left view thereof;

FIG. 6 is a right view thereof;

FIG. 7 is a top view thereof;

FIG. 8 is an enlarged top view thereof;

FIG. 9 is a bottom view thereof; and,

FIG. 10 is an enlarged bottom view thereof.

1 Claim, 8 Drawing Sheets
